UNITED STATES PATENT OFFICE.

WALTER RALPH HERRING, OF EDINBURGH, SCOTLAND.

APPARATUS FOR CHARGING INCLINED RETORTS.

SPECIFICATION forming part of Letters Patent No. 717,575, dated January 6, 1903.

Application filed July 14, 1902. Serial No. 115,486. (No model.)

To all whom it may concern:

Be it known that I, WALTER RALPH HERRING, a subject of the King of Great Britain and Ireland, residing at Granton House, in the city of Edinburgh, Scotland, have invented a new and useful Improvement in Apparatus for Charging Inclined Retorts, of which the following is a specification.

My invention relates to an improved construction and arrangement of coal-charging chute for use in connection with inclined retort installations.

The object is mainly to provide means for varying the inclination of the traversing shoe of the charging-chute, so as to accommodate the varying physical characteristics of the coal used, such variation in inclination being under the control of the attendant and being capable of rapid adjustment by him either prior to or during the actual operation of charging. I attain this object by the mechanism illustrated in the accompanying drawings, in which—

Figure 1 is a side elevation of a coal-charging chute in position having my improvement applied; and Fig. 2 is a cross-section of Fig. 1 on the line *a b*.

Similar letters refer to similar parts in each of the views.

30 A is the shoe, which is secured beneath the body of the traveling chute B and projects into the mouthpiece C of the retort. The nose of the shoe A is pivoted at D and is suspended at each side by a link E, adjustable at F. The upper ends of the suspension-links E are attached at G to the side plates of the hood H, upon which the trolley wheels or runners K are fixed, these wheels or runners K working upon or within guide-rails L, attached to the lower part of the body of the chute B. The suspension-links E serve, therefore, not only as a means of pivoting the shoe A, but also as a means of adjusting the level of the nose of the shoe A to overcome the slight inequalities in level of the various retorts.

The upper end of the shoe A is inclosed

within the aforesaid hood H and moves up and down therein in accordance with the adjustment of a hand-wheel M and screw N **50** or other simple mechanical device. Consequently the angle of inclination of the base of the shoe A is alterable at will, so that the coal descending from the body of the chute B strikes the base of the shoe and is directed **55** into the retort C at whatever angle the shoe A may have been adjusted for. In Fig. 1 the dotted lines at A' indicate the raised position of the shoe A and those at M' and N' the corresponding positions of the hand-wheel M and **60** screw N.

When the apparatus is used in connection with the upper tier of retorts, a handle P is fixed beneath the shoe A. When applied to the middle and lower tiers of retorts, a handle R may be attached to the end plate of the shoe A.

What I claim as my invention, and desire to secure by Letters Patent, is—

1. In apparatus for charging retorts, the **70** combination, with a chute having guide-rails at its lower part, of a hood slideable on the said rails longitudinally of the retorts, an inclined shoe, links pivoting the lower part of the said shoe to the said hood, and means for adjusting the position of the upper end portion of the shoe within the said hood, substantially as set forth.

2. In an apparatus for charging inclined retorts, in combination, the traveling chute B, **80** the guide-rails L thereon, the hood H having wheels or runners K, the shoe A pivoted at D, the suspension-link E adjustable at F, the hand-wheel M having screw N, and a handle attached to the said shoe A, substantially as **85** described, for the purposes specified.

In testimony whereof I have signed my name to this specification in the presence of two subscribing witnesses.

WALTER RALPH HERRING.

Witnesses:

THOMAS ANDREW,
ROBERT J. PHILIP.
